UNITED STATES PATENT OFFICE.

ADOLPH BULOVA, OF NEW YORK, N. Y., ASSIGNOR TO BULOVA WATCH COMPANY, INC.,
OF NEW YORK, N. Y., A CORPORATION OF NEW YORK.

WRIST-STRAP DEVICE.

Application filed March 20, 1926. Serial No. 96,294.

The object of this invention is to improve the straps of men's style wrist-watches so as to make it much more convenient to take the watch off and put it back on the wrist. 5
5 Strap-watches have much advantage over pocket watches and have gained a considerable degree of popularity, but they have a drawback which makes them unacceptable to very many men and which has therefore 10 limited their field to that extent. This disadvantage is the nuisance of unfastening and refastening the buckle with one hand on the numerous occasions when the watch has to be removed or replaced. 15
15 The purpose of this invention, therefore, is to overcome this drawback by the provision of a simple, compact, comfortable, convenient and neat-appearing device, comprising two pivotally folding bars which 20 normally lie folded together beneath the strap, and when unfolded widely separate the ends of the strap members without disconnection, so that the watch and strap will then pass freely over the hand. This unfolding and refolding of the device is accomplished very easily with one hand, and a yielding fastening is provided to hold the bars in folded condition. A means of initial adjustment for one of the strap ends is 25 also incorporated. 30

In the accompanying drawings, forming part hereof:

Fig. 1 is an edge view of a wrist-watch, its strap, and the connection, shown in the 35 condition of wearing, with the connection folded;

Fig. 2 is a similar view showing the connection unfolded and the circuit greatly enlarged to slip over the hand;

Fig. 3 is a rear elevation of Fig. 1;

Fig. 4 is a rear elevation of Fig. 2;

Fig. 5 is an enlarged fragmentary section taken on the line 5—5 of Fig. 3; and

Fig. 6 is an enlarged cross-section on the 45 line 6—6 of Fig. 5.

The strap members 2, 3 are connected to the sides of the watch 4 in the ordinary manner. The other ends of these straps are connected to the broadened terminals 5,

6 of two long, thin, narrow, flexible, curved 50 metal leaves 7, 8. The bodies of the leaves are narrower than the strap members, or the strap members are preferably at least as wide as these bodies. The connection between the terminal 5 and its strap member is 55 preferably permanent, a bar 9 in the terminal passing through a closed loop of the strap-end. The other strap-end is held to the terminal 6 by a pivoted dog or clamp 10 so arranged that the greater the pull 60 upon the strap the tighter the connection. This provides a means of adjustment, whereby the strap member 3 can be drawn in or out of the terminal 6 to obtain the 65 right length for the wrist of the wearer, after which any projecting end of the strap is cut off.

The leaves 7, 8 are adapted to lie snugly together in superposed relation, the convexity of the inner leaf fitting the concavity 70 of the outer leaf, the curvature conforming approximately to the wrist, and the flexibility of the leaves causing them to conform perfectly without discomfort when the strap is closed. 75

The ends of the leaves not engaged with the straps are pivoted together, so that the outer leaf may be swung open and closed. In the preferred construction the hinged end of one leaf is formed with a narrow, 80 thickened tongue, and the leaf 8 with two such tongues, the tongues being of a thickness approximating the combined thicknesses of the bodies of the leaves, and being inter-fitted, and a transverse pivot pin 13 being 85 passed through them, this construction affording a strong, flat, and comfortable hinge.

It is desirable to fasten the two hinged leaves yieldingly together in the folded or 90 closed position. For this purpose a low-lying fastening, lying within the leaves, is provided, the same preferably consisting of a block-like projection 14 on the outer, convex face of the inner leaf 7, remote from 95 the hinge, and a corresponding opening 15 in the outer leaf 8. A longitudinal slot 16 in the inner leaf divides the projection 14

into two halves, so as to afford a degree of resilient compressibility, and the parts have a slight undercut so as to give a snap-fastening effect when the projection is crowded into the opening by closing the leaves together.

In use, the strap and its folding connection are worn as seen in Figs. 1, 3 and 5, with the leaves folded together and caught 10 by their fastening, holding the ends of the strap members 2 and 3 in proximity to each other. To remove the strap-watch the leaf 8 is swung outward by the pull of a finger-nail inserted beneath a lip 17 with which 15 the terminal of the leaf 8 is provided, the fastening 14 and 15 yielding readily to a slight effort exerted in this manner. This carries the ends of the strap wide apart, as shown in Figs. 2 and 4, the ends of the strap 20 still being connected, however. The watch and strap can now be slipped freely over the largest hand, and as easily replaced. To close the strap again, it is simply necessary to fold the leaves together again and 25 press them slightly to engage the fastening, both the opening and the closing operations being of the simplest and quickest character and easily performed by the other hand. The folding of the leaves causes the 30 leaf 8 to carry the strap member 3 over on top of the leaves, the leaves lying folded together and covered and concealed, except at the terminals, by this strap member, as shown in Fig. 3.

35 While the preferred form of the invention has been described in detail in order that there may be a clear understanding of the device, it will be appreciated that various changes may be made by the mechanic skilled in the art without departing from the 40 scope of the invention set forth in the following claims.

What I claim as new is:

1. A wrist-strap device comprising, in connection with two wrist-watch strap members, two long, thin, flexible, curved leaves formed to lie folded face to face in superposed relation, a hinge connecting said leaves at one end of each, connections on the other ends of 45 said leaves to receive the ends of said strap members, the relations being such that in the folding of the leaves the outer leaf carries one of the strap members over on top of the leaves, the leaves lying covered beneath said strap member, one of said leaves having a 50 low fastening projection on its face inwardly of the edges, and the other leaf having a recess to receive said projection.

2. A wrist-strap device comprising, in connection with two wrist-watch strap members, two long, thin, curved, flexible leaves formed to lie folded face to face in superposed relation, a hinge connecting said leaves at one 55 end of each, connections on the other ends of the leaves to receive the ends of said strap

members, the relations being such that in the folding of the leaves the outer leaf carries one of the strap members over on top of the leaves, one of said leaves having a low fastening projection divided by a slot through 70 the leaf, and the other leaf having an opening to cooperate with said projection.

3. A wrist-watch strap device comprising, in connection with two wrist-watch strap members, two long, thin, flexible, curved leaves narrower than said strap members and formed to lie face to face in superposed relation, a hinge connecting said leaves at one end of each, broadened terminals on the other ends of said leaves adapted to receive 75 the ends of said strap members, one of said terminals comprising a clamp for adjustably engaging one of the strap ends, the relations being such that in the folding of the leaves the outer leaf carries one of the strap members over on top of the leaves, the leaves lying covered beneath said strap member. 85

4. A wrist-strap device comprising, in connection with two wrist-watch strap members, two long, thin, flexible, curved leaves formed to lie folded face to face in superposed relation, a hinge connecting said leaves at one end of each, said leaves being narrower than the strap members and having a broadened portion at the end remote from 90 the hinge attachment, connections between the strap members and said broadened portions, one strap member extending over the convexly curved side of the outer of the two folded leaves past the hinge end and being 95 connected with the end of said outer leaf which is remote from the hinge, the construction and relations being such that in the folding of the leaves the outer leaf carries one of the strap members over on top of the 100 leaves, the leaves lying covered and concealed beneath said strap member. 105

5. A wrist-strap device comprising, in connection with two wrist-watch strap members, two long, thin, flexible curved plates formed to lie folded face to face in superposed relation, a hinge connecting said plates at one end of each, attachment connections on said plates to receive the ends of said strap members, one of said connections comprising a clamp adjustably gripping a strap end against one of the plates, one strap extending over the convexly curved side of the outer of the two folded plates, the construction and relations being such that in the 110 folding of the leaves the outer leaf carries one of the strap members over on top of the leaves, the leaves lying covered and concealed 115 beneath said strap member. 120

6. A wrist-strap device comprising, in connection with two wrist-watch strap members, a plurality of long, thin, flexible curved leaves formed to lie folded face to face in superposed relation, a hinge connection between said leaves, firm attachment connec- 125 130

tions between both said strap members and the ends of said leaves, one strap member extending, in the folded condition of the leaves, over the convexly curved side of the outer ⁵ of the two folded leaves and being connected by one of said attachments with the end of said outer leaf which is remote from the

hinge, the construction and relations being such that in the folding of the leaves the outer leaf carries said strap member over on ¹⁰ top of the leaves, the leaves lying covered and concealed beneath said strap member.

ADOLPH BULOVA.
